UNITED STATES PATENT OFFICE

166,924

MAGNETIC CIGARETTE HOLDER

Donald C. Roller, Detroit, Mich.

Application September 7, 1951, Serial No. 16,550

Term of patent 7 years

(Cl. D85—8)

To all whom it may concern:

Be it known that I, Donald C. Roller, a citizen of the United States, residing at Detroit, in the county of Wayne and State of Michigan, have invented a new, original, and ornamental Design for a Magnetic Cigarette Holder, of which the following is a specification, reference being had to the accompanying drawing, forming part thereof.

I claim:

The ornamental design for a magnetic cigarette holder, as shown.

DONALD C. ROLLER.
